(57) **CLAIM**

The ornamental design for a cup holder, as shown and described.

DESCRIPTION

FIG. 1 is a front view of a cup holder showing our new design according to a first embodiment;

FIG. 2 is a rear view thereof;

FIG. 3 is a left side view thereof;

FIG. 4 is a right side view thereof;

FIG. 5 is a top plan view thereof; and

FIG. 6 is a bottom plan view thereof.

FIG. 7 is rear, left and top perspective view thereof;

FIG. 8 is front, right and bottom perspective view thereof; and,

FIG. 9 is rear, right and bottom perspective view thereof.

The broken lines in the figures illustrate portions of the cup holder that form no part of the claimed design.

1 Claim, 9 Drawing Sheets
